TO ALLIS-CHALMERS MANUFACTURING COMPANY, A CORPORATION OF DELAWARE.

SLOT-FORMING MACHINE.

1,165,790.

Specification of Letters Patent.

Patented Dec. 28, 1915.

Application filed June 23, 1910. Serial No. 568,439.

To all whom it may concern:

Be it known that I, GUSTAVE J. LUCK, a citizen of the United States, residing at Milwaukee, in the county of Milwaukee and 5 State of Wisconsin, have invented a certain new and useful Improvement in Slot-Forming Machines, of which the following is a specification.

This invention relates to improvements 10 in the construction of slot forming machines, and particularly to improvements in machines for forming a series of substantially radial slots around the periphery of a body of revolution.

15 An object of the invention is to provide a machine, for forming a series of slots in a body, which is simple in construction and efficient in operation.

Another object is to provide a machine 20 in which the pitch of slots cut around a body of revolution can be easily changed and in which the angularity of the individual slots relative to the adjacent radii of revolution of the body can also be changed 25 as desired.

Still another object is to provide a slot forming device which can be applied to an ordinary planer or similar machine, without changing the general structure thereof 30 and so that the normal operation of the machine will operate the device to automatically form the slots at the desired pitch along the body being machined.

A clear conception of one embodiment of 35 the invention can be obtained by referring to the accompanying drawings in which like reference characters designate the same or similar parts in different views.

Figure 1 is a fragmentary front view of 40 a planer having the invention applied thereto, the cleaning device for the cutter having been omitted in order to avoid unnecessary complication. Fig. 2 is a fragmentary side view, partly in section, of the device as shown in Fig. 1 viewed from the 45 right. Fig. 3 is a fragmentary section through the planer bed and work supporting member or plate, showing one of the lifting wedges and operators therefor. Fig. 50 4 is an enlarged end front view of the cutter showing also, diagrammatically, a fragment of a body of revolution being slotted and the center line of the supporting members. Fig. 5 is a front view of the cutter 55 cleaning device, showing the attachment

thereof to a fragment of the supporting frame.

The drawings and specification of this disclosure show the invention applied to a planer of the well known type in which a 60 planer bed reciprocates on a bed plate and passes between two uprights or vertical tool supporting frames. The planer bed is ordinarily provided with a rack and pinion or similar device by means of which the 65 reciprocation of the bed is produced. The extent of travel of the bed is determined by reversing levers and stops at the side of the machine, the stops being adjustable along the length of the planer, thus providing a means for lengthening or shortening the stroke as desired. The work is ordinarily carried directly upon the planer bed, being clamped thereon, and is operated upon by a tool carried between the 70 uprights. The driving and reversing means have been omitted in the present disclosure as they form no part of the present invention and their construction is well known 75 to persons skilled in the art.

Referring to the drawings, the planer bed 42, having the guides 45 formed at the bottom thereof, is adapted to be reciprocated in the usual manner on the bed plate 44, see Figs. 1, 2, 5. The frames or uprights 80 30, 31, project upward from the bed plate 85 44 on either side of the planer bed 42 and are connected by cross ribs 32, 55.

The mounting pin 20 is held with its axis 90 parallel to the travel of the bed 42 by means of the adjusting block 11 through which the pin 20 passes. The nut 53 serves to clamp the pin 20 into the block 11, the clamping being sufficient only to prevent easy twisting of the pin 20 within the block. The 95 overhanging end of the pin 20 is provided with a key 54 by means of which the ratchet wheel 1 is fixed to the mounting pin 20. The disk or other body 52 of revolution is also fixed to the overhanging end of the pin 100 20 by means of the key 54, being prevented from moving longitudinally of the pin 20 by means of a washer 21 and clamping nut 23. The ram 24, which is mounted in a dovetail groove formed in the bottom of the 105 mounting plate 12, contacts with the body 52, being forced against the body 52 by means of a screw 56. This ram 24 serves to stiffen the body 52, thus preventing vibration of the body near the point of appli- 110

cation of the operating tool. The ratchet wheel guard 22 is fastened to the adjusting block 11 and serves to protect the notches 5 of the wheel 1 against possible injury.

5 The adjustable block 11 is slidably mounted in a vertical slot formed in the mounting plate 12. The vertical slot formed in the mounting plate 12 is closed at its upper end by a plate 29 in the center 10 of which the bevel gear 14 is rotatably mounted. The vertical adjusting rod 13, which is fixed to the upper end of the block 11, is threaded along its upper portion and passes through the hub of the gear 14, 15 the threads coacting with internal threads formed within the gear 14. With this arrangement of elements it will be seen that rotation of the gear 14 will cause the rod 13, and hence the block 11 and the elements 20 carried thereby, to move vertically relative to the plate 12. The horizontal shaft 16 is mounted in bearings 17, 18, which are fixed relative to the mounting plate 12. The bevel gear 15, which is fastened to the 25 end of the shaft 16, meshes with the gear 14. The removable handle 19 fits over a square portion formed on the overhanging end of the shaft 16 and serves to rotate the shaft 16 and gears 15, 14.

30 The mounting plate 12 is slidably mounted on the supporting frame 27, which supporting frame is in turn fixed to the uprights 30, 31, and the cross rib 55. The guide bars 25, 26, are secured to the frame 35 27 in such a manner as to form parallel vertical recesses within which the mounting plate 12 coacts and is adapted to be vertically shifted. The guide bars 25, 26, are held in place by bolts 46, the removal of 40 which permits the removal of the plate 12 and the elements carried thereby.

The wedges 34, see Figs. 1, 3, have inwardly projecting lugs 37 and are slidably mounted upon inwardly projecting flanges 45 50 of the frame 27 by means of guides 50 formed on the bottom of the wedges 34 and coacting in grooves formed in the flanges 50. The upper surfaces of the wedges 34 coact with lower surfaces of wedge blocks 55 33 fastened to the bottom of the plate 12. The wedge actuators 36 are fastened to the planer bed 42 at the front end thereof and have upwardly projecting ends which cross the projecting lugs 37 of the wedges 34. The wedges 34, wedge blocks 33 and 60 actuators 36, 51, comprise means for automatically shifting the mounting plate 12 and ratchet wheel 1 a predetermined amount respectively to and from the cutter 38 at the termination of each reciprocation of 65 the cutter.

The broaching saw or cutter 38 is constructed of a series of sections and is mounted on the cutter holder 40, being clamped thereto by means of the plates 39 and clamping bolts passing through the 70 plates. The holder 40 is adjustably fixed to the planer bed 42 by means of bolts 41 which coact in the holding grooves of the planer bed 42 and pass through transverse slots formed in the holder 40. As shown, 75 the cutter 38 is located slightly to the right of the center line 49 of the planer, see Fig. 4, but the cutter may be shifted to any position relative to said center line, within certain limits. The cutter 38 has teeth 80 which increase in height as they approach the front end of the planer bed 42, the difference in elevation between two successive teeth being the amount of feed or of the cut taken by each tooth. In the present disclosure the cutter 38 is provided with a projection 47 formed at one side thereof which adapts the cutter to the formation of slots having notches at the sides thereof as shown in Fig. 4, such slots being particularly 90 adapted for the securing of turbine blades to the slotted member.

The automatic shifting means for angularly shifting the mounting ratchet wheel 1 consists of a pawl 2 which is pivoted to a lever 4 intermediate the ends thereof, see Fig. 1. The pawl 2 is held in coaction with the notches 5 of the wheel 1 by means of a spring 3. The pin 9 pivotally connects the outer end of the lever 4 with the guard 22. 95 The link 6 is clamped in any desired fixed position in a slot 10 formed in the upright 31 by means of a clamping bolt 8. A pin at the lower end of the link 6 coacts in a slot 7 in the lever 4. It will be noted that the link 6 does not swing upon the bolt 8, but this link may be shifted and secured in any desired angular position relative to the bolt 8 by unscrewing and retightening the bolt. 105

The cutter cleaning device, shown in Fig. 5, is driven by a grooved wheel 74 which contacts frictionally with a ridge formed on the upper side of the rail 43. The rail 43 has its upper surfaces parallel with the plane 115 of the ends of the teeth of the cutter 38, thus giving the upper surfaces of the rail 43 a slight pitch toward the rear end of the planer bed 42. The drive wheel 74 is fixed to one end of a horizontal shaft 73 which is 120 mounted in a plate 68. The bevel gear 72 is fastened to the opposite end of the shaft 73 and meshes with a bevel gear 71 fixed to the lower end of the vertical shaft 67. The shaft 67 is mounted in bearings formed one 125 on each of the plates 68, 65, and has a second bevel gear 63 fixed to its upper end. The bevel gear 63 meshes with a gear 62 which is mounted upon one end of a short transverse horizontal shaft 80. The shaft 80 is rota- 130

tably mounted in a bearing formed in one with the plate 65, and has a rope wheel 61 fastened to its outer end.

The bearing supporting plates 65, 68, are each fastened to the cleaner support 59. The cleaner support 59 is slidably mounted in grooves 28 formed in the edges of the guide bar 26, and has a stop 60 at its upper end which projects over a corner of the supporting plate 12. It will thus be noted that as the wheel 74 is advanced along the rail 43, the cleaner support 59 will rise an amount equal to the pitch of the cutter 38. The support 59 and elements carried thereby 15 may, moreover, be lifted bodily from the upper end of the guide bar 26.

The brush frame 69 is pivoted to the outwardly projecting lugs 66 formed on the support 59 by means of pins 75, and may be 20 swung from the position shown in Fig. 5 to a position parallel to the rail 43. The rotary brush 58 is mounted at the end of the brush frame 69 and has a rope wheel 70 mounted concentrically therewith. The driving rope 25 or cable 64 coacts around the peripheries of the wheels 61, 70, and serves to transmit rotary motion between them.

During the operation of the device, the body 52, which is to be slotted, is mounted on 30 the pin 20 so that its periphery lies below the path of the cutter 38. The planer bed 42 is then given the usual reciprocating motion, carrying with it the cutter 38. The reversing stops for the bed 42 are placed 35 approximately in line with the wedge actuators 36, 51, respectively, thus causing the bed 42 to reverse when the actuator 36 has about reached the rear end of the plate 12 in its forward travel, and also when the actuator 51 has reached the position shown in 40 Fig. 2. During the reversing of the travel of the bed 42 after having completed a cut, it is necessary to advance the periphery of the body 52 preparatory to cutting the next 45 succeeding notch. As the cutter 38 leaves the body 52 during forward travel of the bed 42, the wedge actuators 36 strike the projecting lugs 37 and push the wedges 34 forward so that the broadest portions of the 50 wedges are in coaction with the blocks 33. This forward forcing of the wedges 34 raises the plate 12 and the elements carried thereby away from the cutter 38, the plate 12 sliding on the supporting frame 27. During this 55 shifting, the link 6 and pin at the end thereof remain stationary relative to the frame 27, while the pin 9 and pawl 2 move up with the plate 12, the link 4 in the meantime both swinging and sliding on the pin at the lower 60 end of the link 6. Unless otherwise affected, all points on the plate 12 and all elements carried thereby, will travel an equal amount due to the movement of the wedges 34. The pin 9 therefore carries the adjacent end of 65 the lever 4 a distance equal to the travel of

the plate 12, but owing to the location of the pivot of the pawl 2 intermediate the stationary pivot of the lever 4 and the moving pin 9, the pawl 2 travels only a fraction of the total distance covered by the pin 9. Since 70 the end of the pawl 2 coacts with the notches 5 at the periphery of the ratchet wheel 1, and as these notches 5 tend to move a distance equal to the travel of the plate 12, the difference in travel between the pawl 2 and notches 5 coacting therewith, is taken up in 75 rotation of the wheel 1 and hence of the body 52, about the axis of the mounting pin 20. By adjusting the link 6 relative to the slot 7, it will be seen that any desired difference in travel between the pawl 2 and notches 5 can be obtained, thus permitting 80 ready variation of the pitch of the slots being cut around the periphery of the body 52. It will also be noted that with the same setting of the link 6, the pitch will always 85 be equal, providing the same wedges 34 are used.

After the body 52 and the mounting means have been thus angularly shifted, the travel of the bed 42 is reversed, the backward travel being at considerably higher speed than that maintained during forward travel. As the bed 42 recedes to the position shown in Fig. 2, the wedge actuators 90 51 strike the projecting lugs 37, pushing the wedges 34 back so that the narrowest portions of the wedges 34 coat with the blocks 33. During such shifting of the wedges 34, the weight of the plate 12 and of the elements carried thereby, causes the entire 95 mounting means to again approach the path of the cutter 38 until upon reaching the position shown in Fig. 2, the mechanism is again ready for forward travel or cutting 100 stroke.

If it is desired to operate the machine on a body 52 of greater diameter, it is necessary to raise the mounting pin 20 and vice versa. This is done by turning the handle 19, thus causing the shaft 16 and gears 14, 15, to rotate. As the gear 14 is rotated, the rod 13 and elements carried thereby are either raised or lowered, thus raising or lowering the center of the mounting pin 20. During such shifting of the pin 20 the bolt 8 must also be shifted a relative amount in 110 the slot 10.

As the bed 42 travels forward, the grooved wheel 74 is rotated owing to its contact with the rail 43. The contact between these elements is maintained by the weight of the support 59 and the elements carried thereby, which weight acts on the wheel 74. As the wheel 74 is rotated, the rotary motion is 120 transmitted through the shafts 73, 67, 80, gears 72, 71, 63, 62, to the rope wheel 61 and from these through the cable 64 to the brush 58. The rotation of the brush 58 prevents chips or foreign matter from lodging 125 130

in the teeth of the cutter 38. The brush 58 furthermore retains its location relative to the teeth of the cutter 38 due to the pitch of the top of the rail 43.

5 Before the backward travel of the bed 42 is begun, and during lifting of the plate 12, the brush 58 is, in the construction shown, also lifted away from the cutter 38 by the coaction of the corner of the plate 12 under 10 the stop 60, this coaction resulting since the upward travel of the plate 12 is considerably greater than the upward travel of the support 59 due to the pitch of the rail 43.

It should be understood that it is not desired to be limited to the exact details of 15 construction shown and described, for obvious modifications within the scope of the appended claims will occur to a person skilled in the art.

20 It is claimed and desired to secure by Letters Patent,—

1. In a slot forming machine, a reciprocating cutter, means for mounting a body to be slotted in the path of said cutter, means 25 for automatically shifting said mounting means a predetermined amount respectively to and from said cutter at the termination of each reciprocation of said cutter, and automatically actuated means for angularly shifting said mounting means.

2. In a slot forming machine, a movable cutter, means for mounting in the path of said cutter a body to be slotted, means for automatically moving said mounting means 35 away from said cutter, and automatically actuated means for angularly shifting said mounting means a predetermined amount.

3. In a slot forming machine, a reciprocating cutter, means for mounting in the 40 path of said cutter a body to be slotted, means for automatically moving said mounting means away from said cutter, and automatically actuated means for angularly shifting said mounting means.

45 4. In a slot forming machine, a movable cutter, adjustable means for mounting in the path of said cutter a body to be slotted, means for automatically moving said mounting means away from said cutter, and automatically actuated means for angularly shifting said mounting means.

5. In a slot forming machine, a reciprocating cutter, means for mounting in the path of said cutter a body to be slotted, 55 means for automatically shifting said mounting means away from said cutter at the termination of its cutting stroke, means for

shifting said mounting means toward said cutter at the termination of its return stroke, and automatically actuated means for angularly shifting said mounting means.

6. In a slot forming machine, a cutter having a plurality of successive teeth, means for reciprocating said cutter, means for mounting a body in the path of said cutter, 65 the relation of the mounting of said body to the path of reciprocation of said cutter being such that said cutter forms a completed slot in said body during each reciprocation, means for moving said mounting means away from said cutter, and means for angularly shifting said mounting means.

7. In a slot forming machine, a movable cutter, means for mounting in the path of said cutter a body to be slotted, means for 75 automatically moving said mounting means away from said cutter, and means actuated by said automatically moving means for angularly shifting said mounting means a predetermined amount.

8. In a slot forming machine, a movable cutter, adjustable means for mounting in the path of said cutter a body to be slotted, means for automatically moving said mounting means away from said cutter, automatically actuated means for angularly shifting said mounting means, and means for permitting adjustment of the degree of angular shifting of said mounting means.

9. In a slot forming machine, a movable 90 cutter, means for mounting in the path of said cutter a body to be slotted, means for automatically moving said mounting means away from said cutter, automatically actuated means for angularly shifting said 95 mounting means, and means for permitting adjustment of the degree of angular shifting of said mounting means.

10. In a slot forming machine, a movable cutter, adjustable means for mounting in the path of said cutter a body to be slotted, means for automatically moving said mounting means away from said cutter, means actuated by said automatically moving means for angularly shifting said mounting 105 means, and means for permitting adjustment of the degree of angular shifting of said mounting means.

In testimony whereof, I affix my signature in the presence of two witnesses.

GUSTAVE J. LUCK.
